[57] CLAIM

The ornamental design for a combined video camera
and built-in C.D. player, as shown.

DESCRIPTION

FIG. 1 is a right-side perspective view of a combined
video camera and built-in C.D. player, showing my new
design.

FIG. 2 is a left side perspective view thereof.

FIG. 3 is a top plan view thereof.

FIG. 4 is a rear elevational view thereof.

FIG. 5 is a right side elevational view thereof.

FIG. 6 is a front elevational view thereof.

FIG. 7 is a left side elevational view thereof.

FIG. 8 is a bottom plan view thereof.
